UNITED STATES PATENT OFFICE.

ROBERT CAMPBELL, OF ALLEGHENY, PENNSYLVANIA.

GEARING.

SPECIFICATION forming part of Letters Patent No. 292,791, dated February 5, 1884.

Application filed April 12, 1883. (No model.)

To all whom it may concern:

Be it known that I, ROBERT CAMPBELL, a citizen of the United States, residing in Allegheny, in the county of Allegheny and State of Pennsylvania, have invented a new and useful Improvement in Gearing, of which the following is a specification.

My invention relates to gearing in which a double lever is engaged by a grooved or slotted driving head or wheel.

The objects of my invention are the avoidance of a certain amount of friction and provisions for an increase of power or speed in machinery. The mechanism by which these objects are attained is illustrated in the accompanying drawings, which form a part of this specification.

Similar letters refer to similar parts throughout the views.

Figure 1 represents a driving-head forming part of a piston-rod or connecting-rod, and grooved or slotted to engage a double lever in connection with a pitman or connecting-rod. Fig. 2 is a driving-head engaging two levers connected with rods attached to cranks. Figs. 3 and 4 are top views of the same, Fig. 4 showing it in frame. Fig. 5 is a groove-wheel engaging two levers, and Figs. 6 and 7 are end and top views of the same. Figs. 8 and 9 are grooves formed on arcs of one hundred and twenty degrees and ninety degrees, respectively. Fig. 10 is a circle on which the arcs shown in Figs. 8 and 9 are formed. Fig. 11 is a jointed connecting-rod.

As the principles guiding to the adoption and application of these mechanical forms and connections are not obvious nor capable of illustration by model, the steam-engine is referred to and used in illustrating the character and effects of the invention. To this end let us conceive the pitman or connecting-rod of a steam-engine to be separated from the cross-head, and a grooved or slotted driving-head to be substituted for the cross-head, as in Figs. 1 and 2. The groove or slot is constructed, as in Figs. 8 and 9, so that the curves on the opposite sides of the grooves present their terminations or projecting ends toward the bottoms of the opposite curves, the apexes on a common line or on two opposite parallel lines. The action required of the curves being simply hypocycloidal, the points of the projec-

tions may be square-faced, round, or pointed, as they do not act as bearings.

In Figs. 2, 3, 6, and 7, the levers B are fulcrumed on E and operated by the engagement 55 of the arms furnished with the anti-friction rollers P, which receive the action of the curves D, Figs. 1 and 2, &c., when the driving-head A is actuated by the piston or pitman connected with it, or, if in the cam-wheel M, rotary 60 motion is produced by any engaged motor.

The value of the hypocycloidal curve, as here combined with a double lever having a central fulcrum and an action intended by the formation, position, and engagement, as herein 65 shown and described, is not suggested by an inspection of the mechanism or its action, but from an examination of the conditions of the assembled parts and the possible results of their combined action when various forms and 70 proportions are used.

It is a fundamental design to avoid using the crank-circle in the common manner, and to this end use arcs of the circle in converting the piston or pitman action into effective force 75 where economy or expediency requires it. A short arc gains time; a shallow arc gains power. The distance between the centers of two adjacent opposite projections, measured in the line of stroke of piston-action, is the stroke of 80 piston, and this renders it possible to duplicate the number of revolutions of the crank attached by a single piston-stroke; or, in one case, to enlarge the piston-surface two or three fold; or, in another case, to save one-half or two-thirds of the steam, and still obtain the present speed, power, effects, or results; indeed to gain two hundred or three hundred per cent. in power or speed. For example:

	Crank circle.	Lever No.	Lever No.	90
Are	180°	180°	90°	
Pitch	50°	45°	22½°	
Piston-stroke	24 in.	12 in.	8 in.	
Crank	12 in.	12 in.	5 in.	
Full leverage	12 in.	15 in.	9 in.	95

The circle and arcs are on a common radius.

In Figs. 6 and 7 four connecting-rods are shown, but only two are needed, practically, as they are engaged at right angles on the shaft, being engaged in the groove at different angles, one being at full throw and the other at half throw, as shown in the drawings.

I am not aware that a groove-wheel or driving-head having curves and engaging a double lever, in combination with a piston-rod or connecting-rod, as herein described and shown, has ever been used or claimed in the form and for the purposes set forth. Therefore

I claim—

1. In gearing, a double lever, fulcrumed, connected, combined, and engaged in the form, manner, and for the purpose set forth.
2. In gearing, grooves or slots engaging a double lever, in combination with a connecting-rod or piston-rod when the grooves or slots and lever are engaged and of construction and bearing as described and set forth.

3. In gearing, a driving-head, substantially as shown and connected.

4. In gearing, the combination of a pitman or connecting-rod with a crank and with a double lever, substantially for the purposes set forth.

5. In gearing, an apparatus employing hypocycloidal curves, engaged and operated for the purposes substantially as set forth.

ROBERT CAMPBELL.
